UNITED STATES PATENT OFFICE.

PETER ZUCKRIEGEL, OF CLEVELAND, OHIO.

ADJUSTMENT FOR SUSPENDERS.

No. 903,429.

Specification of Letters Patent. Patented Nov. 10, 1908.

Application filed November 21, 1907. Serial No. 403,236.

To all whom it may concern:

Be it known that I, PETER ZUCKRIEGEL, citizen of the United States, residing at Cleveland, in the county of Cuyahoga and State of Ohio, have invented certain new and useful Improvements in Adjustments for Suspenders, of which the following is a specification.

This invention relates to suspenders, and is embodied in a device which is located where the suspenders cross at the back, for the purpose of adjustably holding the suspender straps together, the construction being such that the attachment may be moved up or down to suit the height or shape of the wearer, and also permitting the straps to turn at various angles with respect to each other according to the local conditions.

A further object of the invention is to construct the attachment in a simple and cheap manner, having at the same time a good appearance, and also capable of being worn either side out, and with no sharp corners or projections to annoy the wearer or to wear out the shirt or coat.

The invention includes plates pivoted together, and a feature thereof is the manner in which the pivotal connection is formed, having decided advantages over an ordinary rivet or screw.

Various other novel features and advantages will appear from the following description, and the accompanying drawings.

In the drawings, Figure 1 is an elevation showing the crossed suspender straps with the device applied thereto. Fig. 2 is a plan of the device with the straps removed. Fig. 3 is a sectional view illustrating the manner in which the plates are connected together. Fig. 4 is a sectional view of the device and the straps applied thereto.

Referring specifically to the drawings, 6 indicates the suspender straps each of which is continuous, and which are crossed at the back. The connecting device consists of two circular plates, of which one is indicated at 7 and the other at 8. These plates are formed of thin sheet metal, as thin and as light in weight as the conditions of strain will permit. With an exception to be referred to hereinafter, the plates are alike in all respects, and when put together will look alike on both sides and can accordingly be worn either side out. Each plate has a circular bead 9 pressed or struck up therefrom, and extending around the plate near the outer

edge thereof. This bead is shown as circular, and this is believed to be the best and neatest, but it may be made in square or other non-circular forms. One object of the bead or rib is to give strength to the plates and to prevent the bending or buckling thereof. A further object of the bead is to provide a rib or raised portion through which the suspender straps pass, and by means of which the position of the attachment with respect to the suspender straps is adjusted. Each bead has two slots at diametrically opposite sides, the length of the slots being sufficient to allow the suspender straps to pass therethrough. The outer slots 10 are located flush with the surface of the plate, while the inner slots 11 are raised slightly above the surface of the plate, whereby the suspender strap, passing through the slot, makes a short bend or kink, causing the strap to bind against the edge of the slots and producing a tension or friction which prevents the device from slipping or moving along the straps unintentionally, or without special effort. As shown, these ribs or beads are formed on the opposite outer sides of the device, so that the inner face or surface of the plates is left flat and smooth, whereby they may turn freely one upon the other.

One plate has at the center a circular opening 12, and the other plate is stamped or formed with a projecting eyelet 13 of proper size to fit through said opening 12. The parts are assembled as shown in Fig. 3, 90 by passing the eyelet through the opening, after which the flange of the eyelet is spun or pressed down over the adjacent edge around the opening 12, to hold the plates together, but sufficiently loose to allow the plates to turn with respect to each other, the eyelet forming the pivot of the turning action. The eyelet is made of considerable size or diameter, as compared to the total diameter of the plate, and is much superior 100 as a pivotal connection to a rivet or screw. By making the eyelet large the outer edges of the plate will not easily spring or spread apart, but will at all times remain in flat shape and close contact so as to form a thin 105 attachment which will not cause annoyance by pressing on the back of the wearer.

It is obvious that the binding friction or engagement of the straps against the edges of the slots 10 and 11 will increase with 110 pull on the straps, and this holds the attachment in place and counteracts its natural

tendency to slide or move down toward the lower end of the straps. The adjustment may, however, be readily effected by pushing in the straps at one side of the bead and 5 pulling the same out at the other, and so the straps may be taken up to put the connecting device in the position desired and for the reasons above stated it will stay where it is put.

10 I am aware that heretofore clasp attachments have been made, and designed for use at the crossing of suspender straps, and having two or more parts pivoted together with pins or rivets, and having for their object 15 to produce or allow automatic adjustment of the clasp, by having the openings through which the suspenders pass so large that the straps will freely slide therein, expecting thereby that through the movement of the 20 body the device or attachment would adjust itself up or down and always return to proper position; but this object is not attained, because by reason of gravity and the pull on the suspenders, such automatically 25 adjustable attachments will always drop to the lowest point permissible by the cross tension of the straps, and will never work back up to the position necessary to prevent the suspenders from slipping off the 30 shoulders, which is the prime purpose of the crossing attachment.

In my invention, the attachment is adjustable so that it may be set high or low on the straps according to the wearer, but it 35 will remain permanently where it is set, allowing, however, any necessary pivotal motion incident to the movement of the body of the wearer. The construction may be placed high on the back to prevent the sus-

penders accidentally slipping off the shoulders of a man with greatly rounded or sloping shoulders, at the same time allowing a free and easy sidewise movement of the straps.

I claim:

1. A suspender attachment comprising a pair of plates having beads provided with slots to receive the suspender straps, one plate having a circular opening at the center and the other plate having a continuous circular eyelet formed integral therewith and extending through said opening and lapped over the adjacent edge of the plate, forming a pivotal connection between the plates.

2. A suspender attachment comprising a pair of plates pivoted together, each having a bead provided with slots for the passage of the suspender strap therethrough.

3. An attachment for crossed suspender straps, comprising a pair of plates pivoted together at the center, each plate having a bead with slots, on opposite sides of the pivot, through which slots the straps extend, across the pivot.

4. An attachment for crossed suspender straps, comprising a pair of plates pivoted together, each plate having an outwardly-extending bead provided with slots through which the suspender straps extend, the slots being located out of alignment with each other, to bind the straps at the edges of the slots.

In testimony whereof I affix my signature, in presence of two witnesses.

PETER ZUCKRIEGEL.
